FIG. 2

FIG. 3

FIG. 1 is a side elevational view of a toy dragline, showing my new design;

FIG. 2 is a top perspective view; and

FIG. 3 is a bottom perspective view.

The side not shown is substantially identical in appearance to the side shown.

The broken line showing of a hand in FIG. 1 is for illustrative purposes only.

I claim:

The ornamental design for a toy dragline, as shown and described.
